COMBINATION SAGGER AND SETTER FOR
BISQUE FIRING VITRIFIED CHINAJohn R. Gednetz, Glendale, Calif., assignor to
Gladding, McBean & Co., Los Angeles, Calif.,
a corporation of California

Application November 20, 1940, Serial No. 366,429

14 Claims. (Cl. 25—153)

My invention relates to the manufacture of vitrified china bisque. In the manufacture of this type of china it has been difficult to produce plates having the so-called flat rims, that is, rims with but little upcurve. In the prior practice there has been a great loss due to the uneven shrinking of the plates and uneven support by the setter which caused a distortion or warping of the plates. For instance, one cause of the warping is due to the plate sticking more or less on one side of the setter and the contraction causing the other side to move inwardly on the setter to a greater extent than desired. Thus as the plate is unevenly supported in the setter when subject to the firing heat, it sags to conform to the shape of the supports.

My invention of the combined sagger and setter of the particular design eliminates entirely the use of silica powder or sand on which the plates may be bedded to form a bung, that is, a stack of the plates usually 8 to 16 high and enclosed by the sagger. Such a manner of firing bisque china results in a considerable wastage through non-uniformity of product, warping, etc. Also in this former practice silica or sand dust is a decided hazard to the operators, it being difficult to prevent silicosis.

I designate my invention as a combination sagger and setter in that the upper or obverse surface forms an individual setter for each plate and the outer flange together with the ledge for stacking develops an enclosing sagger. The combined structures thus when built up form a bung or stack of the desired number of plates, each supported on its own combined sagger and setter. An object and feature of my invention is the construction of a sagger and setter which will have a center support for the well of the plate when this drops under the influence of the heat, this center support having a peripheral shoulder which engages the foot at the margin of the well of the plate. Therefore in the contraction during firing the foot becomes caught by the shoulder causing centering of the plate developing an even contour necessitated by the shape of the setter. Another feature of my invention is in the type of rim support for the rim of the plate at the peripheral portion of the setter, this being so shaped on its upper surface that as the plate contracts, the rim of the plate sags downwardly and becomes of a shape complementary to the rim support of the setter, this giving an even shape to the rim when the foot is properly centered by engaging the shoulder at the center support for the well of the plate.

Another feature of my invention is providing an annular groove or depression at the periphery of the rim support. This is so shaped that it provides a clearance for the fingers of the operator in placing the unburnt plate on the setter. Such construction also permits the operator to properly center the unburnt plate on the setter so that it will have the uniform contraction towards the center and thus cause the peripheral edge of the plate rim to ride inwardly on the rim support. Other features of my invention comprehend providing an annular space between the shoulder of the setter surrounding the center support and the rim support, this being to accommodate the foot of the unburnt plate and to allow movement of such foot in the firing. The foot of the plate settles downwardly as well as pulls inwardly but at no time touches the bottom of this annular depression. This construction causes the bowl of the plate to acquire the shape as designed and to maintain substantially a similar contour in the finished plate as in the unburnt plate with but slight change due to the shrinkage.

Another detail feature of my invention is that when the unburnt plate is properly centered it is supported entirely by the outer edge portion of the rim support of the setter. This positions the well of the plate above the center support of the setter and locates the foot of the plate in the annular recess surrounding the shoulder of the center support. The construction of the setter also provides a notch on the upper portion of a depending flange so that the setters may be stacked one above the other, there being sufficient clearance that an upper setter can in no wise touch the plate on the setter next below.

My invention also comprehends the method of bisque firing in the provision for centering the article by the foot of the plate and therefore causing an even settling downwardly of the rim as well as the well of the plate in a concentric manner. My combined sagger and setter may be made by casting in plaster molds, or it can be made by dry pressing, or wet pressing in mechanical presses with steel dies. Furthermore, should any warpage or distortion of the combined sagger and setter take place during the drying, or firing, it is possible to economically grind the supporting surfaces, such as the rim and the base to a true surface, in order that the vitrified ware fired on the setter may be formed in a true and accurate shape.

My invention is illustrated in connection with the accompanying drawing, in which:

Fig. 1 is a side elevation broken away showing

part of a stack of combined saggers and setters illustrating a half section with an unburnt plate on the upper and a finished plate in the lower setter.

Fig. 2 is a plan of the sagger and setter of Fig. 1 having a shape to make a conventional square plate.

In the construction illustrating the sagger and setter it is of course made in the proper peripheral shape for the shape of the plate to be fired therein. The sagger and setter designated by the numeral 11 has a flange 12, this having a slight upward taper. A peripheral ledge 13 is used for supporting the sagger and setter next above. Above this and extending inwardly there is an annular groove or depression 14 to accommodate the fingers of the operator placing the plate. The rim support 15 has an upper surface 16 with a slight concave curve considered in radial direction, this being to support the rim of the plate. The center portion of the setter has a centering support 17 with a peripheral shoulder 18 extending downwardly therefrom. The upper surface of the center is preferably flat to make a thin flat bottom plate. An annular recess 19 is formed between the shoulder 18 and the inner edge of the rim support. This is illustrated as having a straight downward slope 20 and a horizontal bottom 21 leading to the shoulder 18. This shoulder is slightly tapered upwardly. The material of the sagger and setter is made substantially of uniform thickness which develops a somewhat deep annular space 25 below the rim support 15, the clearance space or groove 14 and there is a central space 26 inside of the shoulder 18. On account of there being a rather deep annular recess 19 there is the annular depressed section 27, however it will be noted that no point of the sagger and setter can contact the plate next below in any stages of the operation.

In order to identify the function of the various portions, an unfinished plate is indicated by the numeral 30. This has a well 31, an annular foot 32, an upwardly curved bowl portion 33 and the rim 34. The peripheral rim edge 35, it will be noted, projects beyond the outer edge of the rim support, that is, beyond the surface 16 extending well over the groove 14. This allows the operator to place the plate by gripping the edge with the finger tips and accurately centering the plate in reference to the rim support and the sagger as a whole. As is well known in the art, there is a quite decided contraction and shrinkage in bisque firing of vitrified china so that although the edge 35 projects well beyond any supporting surface, the contraction of the plate pulls this inwardly.

It will be noted that the rim 34 of the plate is supported and contacts the setter at the outer edge of the surface 16 of the rim support so that the inner portion of the plate rim is entirely unsupported and the outer portion towards the edge 35 is also unsupported. The well 31 of the plate is also positioned above the well support 17, however this plate is accurately centered with the foot above the annular recess 19 and spaced well from the annular shoulder 18 of the center support.

The distance across the setter from the shoulder 18 is always slightly less than any possible distance between the foot 32 when the plate has contracted the maximum amount, therefore in the contraction in firing at least one portion of the foot 32 will engage a portion of the shoulder 18. This causes an accurate centering of the plate as the well portion sinks downwardly and

rests on the center support 17 and also causes the rim 34 of the plate to pull it evenly on the rim support 15. The plate rim settles downwardly so that there is a complete annular surface support on the rim support of the setter. There is however no direct support for the bowl of the plate above the recess 19 and no direct support for the foot of the plate above the bottom portion 21 of this recess. The construction however allows for the proper contraction and settling of the plate so that there is no chance of it being unevenly centered on the setter, hence as the setter is uniform, the plates will all have the same uniformity as they contract to the final measurement as indicated by the lowermost plate in Fig. 1.

It will be noted by the above description that substantially the same design of the setter is suitable for round plates, the construction illustrated in Fig. 1 showing in section substantially a diameter line. This type is suitable for a plate which has quite a pronounced concave portion in the ball of such plate. It will be noted that the setter at the flange 12 is somewhat tapered so that when these are stacked the operator may engage the lower edge of each flange in placing this in a stack or removing the same.

My invention, also it will be noted, includes an improvement in the method of bisque firing vitrified china in that I control the concentric shrinking and downward settling of articles such as the plate. For instance I have provision for setting the unfired article with the rim edge projecting beyond the rim support of the sagger. Then on firing as the well of the plate and the foot settles downwardly, I positively stop the shrinkage laterally by the portion of the foot which first engages the rim surrounding the well support of the sagger and setter, hence the remaining portion of the foot is brought into substantially concentric relation to the shoulder and an even support given to the well of the plate. This centering action causes the rim as it shrinks and settles downwardly to be drawn inwardly evenly and concentric with the center of the plate, the rim conforming to the obverse surface of the rim support of the setter. It will thus be seen that the obverse side of the setter as to the well support and the rim support gives adequate support and shaping to the reverse side of the plate in regard to the well and a portion of the rim, hence as the unfired plate is made of the desired thickness to have the proper contraction, the finished plate is therefore governed as to its shape by the contact surfaces on the obverse side of the sagger and setter.

Various changes may be made in the details of the construction without departing from the spirit or scope of the invention as defined by the appended claims.

I claim:

1. A combination sagger and setter having a peripheral support for the rim of a footed plate with a grooved portion for the operator to center the plate and to accommodate his fingers, the sagger having a center portion with a shoulder to engage the foot of a plate on shrinking and thus retain the plate on complete shrinking centered as to the sagger and setter.

2. In a device as described, a sagger and setter having a peripheral somewhat flattened rim support portion with an annular downwardly extending groove to accommodate the fingers of the operator setting a footed plate with the rim of the plate to rest on the rim support of the

sagger, the sagger having a central portion with a peripheral shoulder to engage the foot of a plate on shrinking of such foot and thus form the centering support for the plate.

3. A combination sagger and setter for bisque firing vitrified footed china having an annular rim support shaped to conform to the reverse side of the rim of the china article, a center support substantially the shape on its obverse surface of the reverse side of the well of the article and having a shoulder to engage the depending foot of the china article, the rim support being adapted to form the entire support for the unfired article with the rim of the article engaging the outer portion of the rim support and the main portion of the rim of the article positioned above the upper surface of the rim support, the article on firing being adapted to settle downwardly and to shrink inwardly with the foot engaging the said shoulder and thereby centering the article, the well of the articles contacting the well support and the rim of the article conforming on its reverse side to the shape of the rim support.

4. A combination sagger and setter for bisque firing vitrified footed china having an annular rim support shaped to conform to the reverse side of the rim of the china article, a center support substantially the shape on its obverse surface of the reverse side of the well of the article and having a shoulder to engage the depending foot of the china article, the rim support being adapted to form the entire support for the unfired article with the rim of the article engaging the outer portion of the rim support and the main portion of the rim of the article positioned above the upper surface of the rim support, the article on firing being adapted to settle downwardly and to shrink inwardly with the foot engaging the said shoulder and thereby centering the article, the well of the article contacting the well support and the rim of the article conforming on its reverse side to the shape of the rim support, an annular groove positioned outside of the rim support and giving the clearance space for the fingers of an operator placing the article on the combination setter and sagger.

5. In a combination setter and sagger for firing footed china articles having an annular rim support, a central well support and a shoulder, the said shoulder being adapted to engage the foot of a china article on shrinkage and settling with the well of the article supported by the well support and the rim of the article conforming on its reverse side to the obverse shape of the rim support.

6. In a combination setter and sagger for firing footed china articles having an annular rim support, a central well support and a shoulder, the said shoulder being adapted to engage the foot of a china article on shrinking and settling with the well of the article supported by the well support and the rim of the article conforming on its reverse side to the obverse shape of the rim support, an annular groove positioned beyond the periphery of the rim support providing a space for the fingers of an operator to center an unfired article.

7. A combination sagger and setter having means on its obverse face to form supports for the reverse side of an unfired and a fired china article, there being a peripheral groove to accommodate the fingers of an operator when setting and centering an unfired article.

8. A combination sagger and setter having

means on its obverse face to form supports for the reverse side of an unfired and a fired china article, there being a peripheral groove to accommodate the fingers of an operator when setting and centering an unfired article, a supporting surface on the outside of the said groove adapted to engage and support a sagger next above.

9. A combination sagger and setter having surfaces on its obverse side to support an unfired article and to engage a plurality of surfaces on the reverse of the fired article after shrinking and settling, there being a peripheral flange on the sagger and setter having a stacking surface on its upper portion for stacking the saggers and setters one above the other, each sagger and setter having a groove positioned inwardly of the said stacking surface to accommodate the fingers of an operator when setting an unfired article on the obverse surface of the setter and sagger.

10. In the method of bisque firing vitrified china comprising supporting an unfired article by the reverse side of its rim, causing the article to shrink in diameter and to settle downwardly when fired, restraining the inward movement of part of the article when shrinking and thereby cause the while article to shrink and settle downwardly concentric with its center.

11. In the method of bisque firing vitrified footed china comprising centering as unfired plate-like article with the rim of the plate extending beyond a rim support of a sagger and setter, on firing causing the plate-like article to contract in diameter and to settle downwardly, bringing at least a portion of the foot of the article at one side in engagement with a centering stop and hence causing the article to contract uniformly as to its center and to settle downwardly uniformly as to its center thereby forming a rim of uniform depth relative to the well of the article.

12. A combination sagger and setter having an annular supporting surface adapted to support the rim of a footed article to be fired, and an upright annular shoulder disposed below and within said surface arranged to be engaged by the foot of the article during contraction of the article while it is being fired so as to center the article during firing and contraction with relation to the sagger and setter.

13. A combination sagger and setter having an annular supporting surface adapted to support the rim of a footed article to be fired, and an upright annular shoulder disposed below and within said surface arranged to be engaged by the foot of the article during contraction of the article while it is being fired so as to center the article during firing and contraction with relation to the sagger and setter, said sagger and setter being relieved outwardly of said supporting surface to provide a finger-receiving space in positioning an article to be fired thereon.

14. A combination sagger and setter having an annular supporting surface adapted to support the rim of a footed article to be fired, and a central supporting surface designed to support the center of the article, said central supporting surface terminating at its edges in an upright shoulder engageable by the foot of the article on contraction during firing so as to center the article with relation to the sagger and setter.
